UNITED STATES PATENT OFFICE

2,465,206

BUILDING BOARD POSITIONER

Ira D. Davis, Avery, Tex.

Application April 15, 1946, Serial No. 662,272

5 Claims. (Cl. 304—9)

1

This invention relates to building apparatus and has reference to a device for positioning building board, such as Sheet Rock, Beaver Board, and the like when nailing or otherwise securing the same during the construction of a building.

The primary object of the invention is to provide a device of the referred to class for the convenient installation of building board.

Another object of the invention is to provide a machine or device whereby one man can handle and install building board when securing the same, either overhead or as walling.

A particular feature of the device resides in a pivoted guide which will support the building board when the latter is in a vertical position, but which guide will partially rotate when in a horizontal position so as not to interfere with overhead installation.

A further object of the invention is to provide a base which ordinarily has casters equally spaced with respect to the base's center, but which are capable of automatically changing their relation when the device is moved against a wall, such as when installing building board or shiplap on walls.

A further object of the invention resides in the versatility of the device whereby the same may be collapsed for transporting, and extension means whereby building board may be installed at various heights.

These and other objects of the invention will become apparent from the following description of the accompanying drawings, wherein:

Figure 1 is an elevational view of the back of the invention and particularly showing the construction of the frame and the hoisting mechanism.

Figure 2 is an end elevational view of Figure 1 and particularly showing the pivoted guide attached to the frame, and further illustrating the sliding movement of certain of the supporting casters in dotted lines.

Figure 3 is an end elevational view similar to the top portion of Figure 2 and showing the relative position of the guide when the building board is horizontally supported by the frame.

Figure 4 is an elevational view of the frame in its collapsed position.

Figure 5 is a broken perspective view of a portion of the base and particularly illustrating the trigger mechanism for moving certain of the casters, and,

Figure 6, is a broken side elevational view of two of the extensions in their assembled position.

Accordingly, the invention includes a base 1 having radially disposed legs 2 and a vertically positioned standard 3 projecting upwardly from the center of the said base. Casters 4 are secured to the lower undersides of the legs 2 in the man-

2

ner shown in Figures 1 and 2, for conveniently rolling the device from place to place.

Opposing legs 2 of the base 1 are dovetailed to slidably receive a guide 5 to which two of the casters 4 are attached. As particularly shown in Figure 5 the guide member 5 is provided with a trigger mechanism consisting of a bell crank 6 secured by a pivot pin 7 to the underside of the said guide. One end of the crank 6 is pivotally connected with a rod 8 which extends lengthwise of the guide 5 and terminates in an integral and laterally positioned button 9.

The rod 8 is slidably supported by a bearing 10. The other end of the bell crank 6 is notched to receive a downwardly projecting pin 11 permanently secured to the underside of the leg 2. By this arrangement the casters 4 may be spaced equally from each other for rolling the device from place to place. However, as will be seen in the description of operation, the sliding feature of the guide 5 and its attached casters 4 is for conveniently securing building board or the like to vertical parts of the building under construction. When the guide 5 is in its extended position, as shown by dotted lines in Figure 2, a door stop mechanism 4a or the like, attached to the base 1 prevents tilting, and further prevents the casters 4 from rolling.

Referring now to Figures 1 and 2, the vertical standard 3 telescopically receives one or more extensions 12, each of which has a projecting rack gear 13 along one side. As shown in Figure 2 one side of the standard 3 is opened to receive or remove the extensions 12, one at a time, when a multiple of the same are employed.

Near the upper end of the standard 3 and integral therewith, there are corresponding ears 14 which rotatably receive a horizontal shaft 15. Between the ears 14 and mounted on the shaft 15 there is a pinion 16, and outwardly of one of the ears 14 there is a crank 17 rigidly secured to the said shaft. Above the pinion 16 and similarly supported by other ears 18 and a pin 19 therethrough, there is a pawl 20, the end of which engages the teeth of the pinion 16. By this arrangement the extensions 12 may be maintained in their raised position by reason of the ratchet effect of the pawl 17.

As will be noted in Figure 6 one end of each extension 11 is provided with a longitudinal pin 21 which fits into a corresponding opening 22 in the other end of each of the said extensions. The uppermost longitudinal pin in the assembly 22 receives therearound a collar 23 as shown in Figure 1 on the shoulder of the extension body 12, and supports a compression spring 24 positioned around the said pin.

Another collar 25 is similarly positioned around the referred to pin 21 for slidable movement thereon, and slidably supports a cross member 26 of a frame assembly 27. The frame 27, which is

3

substantially rectangular in shape, is pivotally secured to the cross member 26 by a hinge 28, as shown in Figure 2. Preferably, the cross member 26 has a broad upper surface, the purpose of which will become apparent in the description of operation.

The frame assembly 27 includes parallel upper and lower members 29, and parallel end members 30, all of which are pivoted at their respective corners by means of pins 31. Central frame member 32 is similarly pivoted by pins 33 to the upper and lower members 29 and is parallel with respect to the end members 30. The hinge 28 is attached to the lateral member 32 for supporting the frame 27.

Projecting from each end member 30, and located intermediate the hinge 28 and the lowermost frame member 29, there are pins 34 which pivotally support guides 35, which guides are diagonally shaped along corresponding sides, substantially as shown in Figure 3. Each guide 35 includes an upwardly and outwardly projecting lug 36 at one end, and a downwardly or inwardly projecting lug 37 at the other end. Additionally, the lower or outer ends of the guides 35 may include a connecting brace 37 connected thereto so as to cause the two guides to operate in unison. The brace 37 is detachably secured by any suitable means (not shown).

A hook type brace 38 may be secured to one of the frame members, such as 30, at its one end by an eye screw 39, whereas the hook portion of the said brace engages another eye screw 40 secured to another of the frame members, such as 29.

Reference is now made to Figure 4 wherein the frame assembly 27 is shown in its collapsed position. The hook brace 38 is detached from the eye screw 40 at its hooked end, and by reason of the described pivoted parallelogram construction of the said frame, the latter may be folded as shown.

In carrying out the scheme of collapsibility, the cross member 26 may be detached from the hinge 28 and lifted from the extending pin 21. The attachment between the standard 3 and the base 2 may be such that the last referred to parts may be detachably secured by suitable means (not shown) for further carrying out the collapsible feature of the invention.

In operation, the device is assembled as shown in Figures 1 and 2, with the frame 27 in its vertical position. A sheet of building board 41 is placed vertically upon the outwardly projecting lugs 36 of the guide members 35 and, when attaching the said board overhead, the frame is tilted to a horizontal position. In so doing, the inwardly projecting lugs 37 of the guides 35 contact the frame supporting cross member 26, causing the outwardly projecting lugs 36 to move below the lower plane of the building board 41. The crank 17 is then turned, lifting the cross member 26 and the frame 27, and thus placing the board 40 against ceiling joist where the same is to be secured.

The slideable pin action within the cross member 26, together with the action of the compression spring 24, allows the building board 41 to be held in place under spring tension. The pawl 20 engages the crank gear 16 holds the frame 27 in its upwardly extended position, thus allowing the workman to use both of his hands for nailing.

To lower the frame 27 after nailing, the pawl 20 is disengaged and the said frame is lowered by means of the crank 17.

When securing building board 41, shiplap or the like, to a vertical surface, such as a wall, the board is placed upon the guides 35 in the manner previously described, but the frame is not tilted.

5 While in this position the device is rolled to the wall where the button 9 of the base assembly contacts the said wall, and through the medium of the rod and bell crank previously described, allows the caster supporting guide 5 to slide as 10 shown in Figure 2. The stop 4a is then depressed so as to prevent tilting or rolling of the device, and by means of the crank, the board 41 is raised vertically to the position where it is to be nailed. After nailing, the frame 27 is lowered by means 15 of the crank 17.

What I claim is:

1. In a positioner for installing building board or the like, the combination of a standard, a vertically disposed and movable extension forming a part of the said standard, and a frame pivoted to the upper end of the said extension and selectively extensible lugs connected with the said frame for supporting and engaging the building board when the said frame is in its tilted or vertical position.

2. In combination with a positioner as defined in claim 1, a base supporting the named standard, casters supporting the said base, and a slideable guide within the said base and supporting certain of the said casters.

3. In combination with a positioner as defined in claim 1, a base supporting the named standard, casters supporting the said base, a slideable guide within the said base and supporting certain of the said casters, and a lock mechanism for detachably engaging the said guide with the said base.

4. In a positioner for installing building board or the like, the combination of a base, casters supporting said base, a standard extending upwardly from said base, a vertically movable extension forming a part of said standard, a tiltable frame hingedly secured to the upper end of the said extension, and selectively extensible guide means attached to said frame for engaging building board or the like when the said frame is in a tilted position.

5. In a positioner for installing building board or the like, the combination of a vertically extensible standard, a pin vertically disposed at the upper end of the said standard, a lateral cross member engaged by said pin, a frame hingedly secured to the said cross member, guide members having diagonal sides pivotally attached to the said frame at each end thereof, and projecting lugs on the said guide for engaging building board when the said frame is in its tilted or vertical position.

IRA D. DAVIS.
